(57) **CLAIM**

The ornamental design for a shoe bottom, as shown and described.

DESCRIPTION

FIG. 1 is a bottom perspective view of a shoe bottom showing our new design;

FIG. 2 is a bottom plan view thereof;

FIG. 3 is a right side elevational view thereof;

FIG. 4 is a left elevational view thereof;

FIG. 5 is a front elevational view thereof; and,

FIG. 6 is a rear elevational view.

The broken lines showing the upper in the figures are for illustrative purposes only and form no part of the claimed design. The circular shapes in FIGS. 1, 2, 5, & 6 are understood to represent semi-spherical shapes when viewed from the sides.

Any unshaded portions of the interior surfaces of the shoe bottom do not form any part of the claimed design.
